(57) **CLAIM**

An ornamental design for a surgical headrest pad, as shown and described.

DESCRIPTION

FIG. 1 is a perspective view of the surgical headrest pad showing the inventive design thereof;

FIG. 2 is a first end elevation view thereof;

FIG. 3 is a second end elevation view thereof;

FIG. 4 is a first side elevation view thereof;

FIG. 5 is a second side elevation view thereof;

FIG. 6 is a top view thereof; and,

FIG. 7 is a bottom view thereof.
